COOLER FOR REFRIGERATORS

Robert Horwitz, New York, N. Y.

Application August 4, 1932, Serial No. 627,529

6 Claims. (Cl. 62—141)

This invention relates to containers for cooling articles, particularly liquids, in a usual household refrigerating device, and has for its main object to provide a cooling container of the type mentioned, which will be efficient in use.

My invention particularly aims to provide a device, as characterized hereinbefore, which may be used in mechanical refrigerating household devices and which will occupy the space underneath the usual refrigerating unit in such device, which space normally is hard to make use of for cooling the usual articles placed into such refrigerators, or which space normally is entirely wasted or occupied by a drip pan, or tray.

Another object of this invention is to form said cooling container in such a manner that the same may replace a drip pan and be used for collecting the drippings from the refrigerating unit.

Still other objects of this invention are to provide a device, as characterized hereinbefore, which will be simple in construction, inexpensive, attractive in appearance, handy in use, and from which it will be convenient and easy to withdraw the cooled liquid, and the refilling of which container will be similarly easy and convenient.

Still further objects of this invention will be apparent as the specification of the same proceeds.

In order that its construction and operation may be readily comprehended, I will now proceed with a full, clear and specific description of the invention, having reference to the accompanying drawings, which show an approved, embodiment thereof, and in which:

Fig. 1 is a front elevation of a household refrigerator of the usual make, the door of the same being open and my device being applied therein.

Fig. 2 is a plan view of one embodiment of my device, while

Figs. 3 and 4 are side and front elevations, respectively, of said embodiment.

Fig. 5 is a front elevation of a cap used with this embodiment of my device carrying the liquid discharging and refilling devices, while

Fig. 6 is a cross sectional view of the cap shown in Fig. 5, the section being taken approximately on the line 6—6 of Fig. 5.

Figs. 7 and 8 are plan view and front elevation, respectively, of a modification of my device.

Figs. 9 and 10 show further modifications.

Referring to the drawings by characters of reference, the numeral 10 indicates a refrigerator in general having the usual heat insulated walls,

a heat insulated door 11, shown in the figure in open position, the inside space 12 thereof being kept at a low temperature when the refrigerator unit 13 is in operation. Said refrigerator unit may be any of any of the standard makes, and as usual, shelves 14 are also employed within the refrigerator on which may be placed the various articles 15, which it is desired to keep or preserve at the low temperature within the refrigerator. A narrow space 16 is usually provided underneath the mechanical refrigerator unit 13, in this case it being the space between said mechanical unit and the first shelving thereunder, which space is very awkward and unhandy to be used for placing therein articles or objects to be cooled. Normally, it either goes to waste or a drip pan is put into the same underneath the refrigerating unit 13 to receive the dripping thereof, which are particularly pronounced and of larger quantity when the device is being entirely defrosted, but some such drippings may continually happen during the regular operation of the refrigerator.

The preferred form of my device is simply a flat shaped bottle 17 which is made so that it should fit into the average such space 16 underneath the mechanical unit in a refrigerator and practically fill said space, but should not project beyond the same in a longitudinal direction towards the door of the refrigerator beyond the inner surface of said door when closed, while it should also substantially remain within the confines of the space underneath the refrigerator unit in a transverse direction. A suitable distance will, however, be left between its top surface and the bottom surface of the mechanical refrigerator unit 13.

The bottle 17 may be made of any suitable material, but I prefer to make it of glass so that the contents thereof may be observed therethrough, and I provide the same with a narrower, but still comfortably wide neck 18 having a few screw threads 19 formed thereon for the purpose of receiving a similarly screw threaded sealing cap 20. The bottom wall 21 of the bottle 17 is substantially flat, so that the same may rest thereon when placed on the shelf 14 underneath the refrigerator unit 13, though it may curve somewhat, and the side walls 22 may be rounded, as shown in the drawings, or they may be substantially plain vertical walls, while the top wall 23 of my bottle will be made with a pronounced depression 24, preferably inclining towards the center thereof in both longitudinal and transversal directions, but leaving an intact raised

marginal ledge 25 in the material of the top wall around said depression 24.

The sealing cap 20 may be made of two sheet metal caps 26 and 27, the outer one 26 being of plain but finished appearance, while the inner one 27 alone will have the screw threads 28 to engage the treads 19 on the bottle neck, the two caps 26 and 27 being united by any suitable method, known in the art, as indicated at 29. A sealing rubber disc or washer 30 may be placed within the cap 20 and two registering sets of apertures 31 and 32 may be provided in the bottom walls of the two caps 26 and 27 and in the washer 30.

When the cooler bottle is resting on this bottom wall 21, the smaller set of apertures or holes 31 will be higher than the set of holes or apertures 32, which latter ones are placed low and are of larger diameter than the set of holes 31. A rectangular tube piece 33 is secured in the upper holes or apertures 31 having a flaring and widening vertical branch 34 opening to the outside of the cap and a horizontal cylindrical branch 35 entering the inside of the cap and the bottle neck, the two having rectangularly placed communicating bores 34' and 35'. The horizontal branch 35 has screw threads 36 provided thereon and a securing nut 37 may be threaded on the inner end thereof so as to firmly secure the angular tube piece 33 on the bottom wall of the cap 20 through the cooperation of shoulder 38 on said angular tube 33.

A discharge valve device 39 is secured in a similar manner into the larger hole or aperture 32 having a horizontal bore 40 whereby it constantly communicates with the inside of the bottle, while said valve may have a rotating hollow cone 41, as usual, communicating with said passage or bore 40 through the hole 42 in its wall, when it is in a certain position, in this case when the operating handle 43 of said rotating cone is in the position shown in Figs. 5 and 6, while its hole 42 will be placed out of register with the passage 40 in the normal position thereof and the position 45 of its operating handle 43 in such a case is indicated in Figs. 2 to 4.

In use, my cooling bottle 17 will be placed in the space 16, as described hereinbefore and indicated in Fig. 1, and the cooled liquid contents 50 thereof may at any time be tapped by opening the door 11 of the refrigerator and turning the handle 43 of the discharge valve 39 in a forward opening direction, as indicated in Figs. 5 and 6. The empty bottle or container may be refilled 55 through the funnel 34 which at the same time will allow the air to escape from the space in the bottle and permit its filling with water or other liquid. Funnel 34 and its receiving apertures in the closing cap of the bottle will be placed as high as 60 possible, but still in such a manner that the upper edge of said funnel should not substantially project above the top wall of the bottle. For obvious reasons, and in the same way, the discharge valve 39 and its receiving aperture 32 in the cap 65 20 will be placed as low as circumstances permit.

The drippings from the refrigerator unit 13 will be received by and collected in the depression 24 in the top of the bottle and may conveniently be removed therefrom by any appropriate 70 method.

My cooling bottle or container 17, may, of course, also be made without the depression 24 in its top wall, in which case it will not be used as a drip pan, but simply as a cooling container 75 and may be placed into any appropriate part of

the refrigerator and used to store or rest other articles thereon.

Another change in the construction of my device is illustrated in a diagrammatical manner in Fig. 9 and may consist in connecting the container 17 by pipe line 60 with the usual running water system of the home in which the refrigerator is employed, placing a valve 61 between the same and the running water system and intermittently opening the container to said running water system and permitting it to fill up.

It is also obvious that my container, shaped and constructed as described hereinbefore and adapted to be placed underneath said refrigerator unit 13, may be used to cool any liquid besides water, and it may also be constructed with a larger front discharge opening in such a manner that it may receive other articles desired to be kept in a separate container in the refrigerator, said container according to this invention, using a practically waste space in the inside of said refrigerator.

My invention, finally, may naturally be used in common ice-boxes without a mechanical refrigerating unit.

In Figs. 7 and 8, I illustrate a modified form of my invention in which a cooling bottle 50 is shown with a cap 51, refilling and air discharge opening 52 and top valve 53 generally constructed as described hereinbefore, but the top wall 54 of the bottle is, in this modification, made outwardly declining or convex shaped instead of depressed towards the center, or concave, as is shown in the preferred modification. The drip water in this case, of course, will run towards the outer edges of the bottle and a pan like extension 55 may be added on such sides of the bottle towards which the drip water will run, to receive the same.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various changes in details of construction, proportion and arrangement of parts may be resorted to, when required, without sacrificing any of the advantages of my invention, as set forth and defined in the appended claims.

One such change is illustrated in Fig. 10 and consists in making the funnel 34 of the angular filling tube 33 of a separate piece rotatable in the body 33 and sealed thereagainst, as shown, and in a similar manner to cone 41 of valve 39, an opening 34" may be provided in the wall of the funnel 34 which at a certain position thereof, may communicate with passage 35', while at other positions thereof will be sealed from said passage. This will make it possible to seal the container from the outside when no water is drawn therefrom and so prevent the undesirable odors in a refrigerator from reaching the cooled water. Such a construction may even make it possible to omit the valve 39 from my bottle and control the discharge of the water therefrom through a permanently open outlet by the manipulation of the rotatable funnel 34.

It is also understood that the refilling or so called "breather" device 33 may be placed at any other suitable part of the device besides the front thereof where it is shown in the present embodiment.

What I claim as new is:

1. A cooling container for refrigerators, comprising a hollow body having one substantially flat side adapted to rest on a support in said refrigerator; the opposite top side of said container being outwardly convex, and pan like extensions in cooperation with said hollow body into which said convex top may shed the liquid dripping thereon.
2. In a substantially flat bottomed water cooling bottle adapted to rest on said bottom underneath the refrigerating unit proper in a mechanical refrigerator, and comprising an entirely separate independent element closed in itself, a curved top for said bottle to guide the drippings from said unit, and upwardly open means co-operating with said curved top and located on and associated with the exposed outside surface of the bottle to collect and store said drippings.
3. In a water cooling bottle, as set forth in claim 2, said top of the bottle being convex in shape, and said means to store said drippings being in the form of channels along the outer edge of the bottle.
4. In a water cooling bottle, as set forth in claim 2, said means to store said drippings being in the form of depressions in the top surface of the bottle.
5. In a water cooling bottle, as set forth in claim 2, said top being convexly curved and said means to collect and store the drippings being in the form of extensions to the side surfaces of the bottle.
6. In a water cooling bottle adapted to be placed underneath the refrigerating unit proper in a mechanical refrigerator, a convex top for said bottle adapted to shed the drippings from said refrigerating unit, and means on said bottle cooperating with said convex top to collect and store said drippings.

ROBERT HORWITZ. 20
